UNITED STATES PATENT OFFICE

2,571,008

MARKING DEVICE AND INKER THEREFOR

Merrill E. Boekeloo, San Gabriel, Calif.

Application September 12, 1946, Serial No. 696,525

1 Claim. (Cl. 101—103)

1

My invention relates to marking devices of the general type disclosed in my U. S. Letters Patent No. 2,273,816, dated February 24, 1942, and over which the instant invention is designed as an improvement.

The primary object of the instant invention is to provide a marking device in the form of a hand stamp which is adapted for quick, easy use with one hand for successive marking operations with inked type and for re-inking between marking operations by light finger pressure.

Another object is to provide in a device of the character and for the purposes set forth, an inking roller which is adequately protected against accumulation of dust and dirt thereon and covered so as to prevent the fingers or the hand, or the work, from coming into contact therewith and becoming smeared with ink.

Still another object is to provide for changing the position of the inking roller so that different surface portions thereof will be used in inking and uniformly coated with ink.

Other and subordinate objects, also comprehended by my invention, together with the precise nature of my improvements, and the advantages thereof will be readily understood when the succeeding description and claims are read with reference to the drawings accompanying and forming part of this specification.

In said drawings:

Figure 1 is a view in side elevation of my improved inking device.

Figure 2 is a view in rear elevation.

Figure 3 is a view in vertical section taken on the line 3—3 of Figure 2, and

Figure 4 is a similar view taken on the line 4—4 of Figure 2.

Referring to the drawing by numerals, my improved marking device, or stamp, as shown, comprises a casing 1 of substantially rectangular form, preferably, and of a suitable size for holding in the palm of the hand, said casing 1 including a top 2, sides 3 with lower front corner notches 4 therein of right angled form, a front plate 5 extending from the top to said notches 4 and secured to the sides 3 by side flanges 6 on said plate and screws 7 extending through the flanges 6 and said sides 3, and a lower rear corner bar 8 connecting the sides 3 together. The back and bottom of the casing 1 are preferably open. A rear edge flange 9 on the top 2 extends across the upper portion of the back of the casing 1 to partially close said back.

A yoke 10 of inverted U-shape depends from the top 2 of the casing 1 adjacent the rear of

2

said casing, with the bight 11 thereof detachably secured by a screw 12 to said top 2, and the sides 13 thereof spaced from the sides 3 of the casing 1 and provided with bottom edge notches 14 therein. A flat bar 15 is fitted in said notches 14 with ends 16 turned up against the sides 13 of said yoke 10.

Wheels, as at 17, fitted side by side between the sides 13 of the yoke 10, in the upper portion 10 thereof, and rotatable on a transverse shaft 18 fixed at its ends in said sides 13, support type bands 19 having raised type 20 thereon, and which are trained over said wheels 17 and around the flat bar 15 over which said bands 19 are 15 slideable under rotation of the wheels 17 and which provides a backing for the type 20, located slightly below the bottom of the casing 1 so that selected type 20 positioned below said bar 15 may be pressed against the work, not shown, 20 without the bottom of the casing 1 engaging the work. The bands 19 hold bar 15 in the notches 14. Relatively larger diameter adjusting discs 21 on the sides of the wheels 17 provide for finger adjustment of said wheels to feed the bands 19 and the selected type 20 into printing position beneath the bar 15. A transverse shaft 22 is suitably fixed in the sides 13 of the yoke 10, between the wheels 17 and the bar 15, with its ends seating upwardly in vertical slots 23 in the sides 3 of the casing. The shaft 22 stabilizes the yoke 10, and hence the parts carried thereby, against play in the casing 1 and serves other purposes presently clear.

A U-shaped inking bail 24 is provided in the 35 bottom of the casing 1 with an inking roller 25 thereon on a shaft 26 extending across said bail and journaled in the sides 27 of said bail. The bail 24 has straight sides 27 fitting flat between the sides 3 of the casing 1 and swingably mounted 40 on the shaft 22 so that said bail is swingable downwardly about said shaft from a normal position in which it extends forwardly of the shaft to a depending inking position in which the inking roller 25 engages the type 20 disposed beneath 45 the bar 15. The sides 27 of the bail 24 are adapted to engage the bottom edges of the flanges 6 of the front plate 5 to establish the normal, upswung position of said yoke 10, and to engage the cross bar 8 to establish the downswung, inking position 50 of said yoke. A spring 28 coiled around the shaft 22, between the yoke 10 and one side 3 of the casing 1, and having opposite ends bearing against the shaft 26 and one upturned end 16 of the bar 15, urges said bail 24 into its normal described 55 position. The bail 24 is provided with a front

and bottom bridge portion 29 partially housing the inking roller 25 to protect same against accumulation of dust and dirt thereon, and forming a guard preventing the inking roller 25 from contacting the hand of the user of the device, and also from engaging the work when said bail is in normal position. Hand wheels 30 are provided on the ends of the shaft 26, outside the bail 24, for manually rotating the inking roller 25, for a purpose presently seen.

An ink pad 31 is suitably fixed to the bottom of an inturned bottom edge ledge 32 on the front plate 5, and against which the inking roller 25 is adapted to be yieldingly pressed by the spring 28, into normal position of the bail 24. As will be noted, in the normal position of the bail 24, the bridge portion 29 thereof overlaps the front plate 5 and the sides 27 of said bail overlap the top edges of the notches 4, all to prevent dust from accumulating on the inking pad 31. Also, in the normal position of said bail 24, the bottom edges of the sides 27 are flush with the bottom edges of the sides 3, so that said bail 24 is out of the way when marking with the device. As will be seen, the inking roller 25 may be rotated by the hand wheels 30 against the ink pad 31. This permits the use of paste ink on the inking pad 31 and smoothing such ink on said roller 25 so as to obviate clogging of the type 26.

Finger operated means is provided for moving the bail 24 into inking position, as follows. A substantially triangular rocker plate 33 is swingably mounted on a cross shaft 34 in the upper front corner of the casing 1 alongside one side 3 of said casing, said plate depending from said shaft and having a lower rear, corner lug 35, thereon above and in the rear of the cross shaft 22. A cord 36 is connected at one end, as at 31, to said lug 35, trained under a pulley 32 on the shaft 22, and connected at its other end, as at 39, to one side 27 of the bail 24, between the shaft 22 and the bridge portion 29. A push rod 40 is slidably extended through an opening 41 in the front plate 5 with an inner end pivoted, as at 42, to the rocker plate 33, and an outer end provided with a push-button 43 thereon.

The manner in which the described invention is designed to be used and operated will be readily understood. The proper type 20 are brought to the printing point beneath the bar 15 by rotation of the wheels 17, in a manner which will be understood. In the marking, the casing is grasped in the palm of the hand and the type 20 selected for printing are pressed against the work, not shown, by hand pressure on said casing 1. By exerting rearward pressure on the button 43, through a finger of the hand grasping the casing 1, the push rod 40 may be thrust inwardly of the casing 1 to cause the rocker plate 33 to be swung rearwardly and upwardly. Such swinging of the rocker plate 33 exerts a pull on the cord 36 whereby the bail 24 may be swung into the desired inking position, shown in dotted lines in Figure 3, and in which the inking roller 25 has been caused to wipe over the selected type 20 to ink the same. In the normal position of the bail 24, the inking roller 25 is always maintained against the ink pad 31 so that by rotating said inking roller 25 through the medium of the hand wheels 30 ink may be thoroughly and evenly ap-

plied to any surface portion of said roller. By disconnecting the cord 36 and removing the screw 12, the yoke 10, together with the parts carried thereby, and the bail 24 with the inking roller 25 therein may be removed downwardly from the casing 1 as a unit for cleaning or other purposes.

The foregoing will, it is believed, suffice to impart a clear understanding of my invention, without further explanation.

10 Manifestly, the invention, as described, is susceptible of modification without departing from the inventive concept, and right is herein reserved to such modifications as fall within the scope of the appended claim.

15 I claim:

In a hand stamp, a casing adapted to be held in the hand and having an open bottom, marking means at the bottom of said casing for pressure against work to be marked by hand pressure exerted downwardly against the casing, and means for applying ink to said marking means comprising a transverse inking pad in said casing, a bail, means pivotally mounting said bail in said casing for swinging upwardly and downwardly into and out of the bottom of said casing respectively, a roller mounted in said bail for engagement with said pad by upward swinging of said bail and for rolling engagement with said marking means by downward swinging of said bail, spring means for swinging said bail upwardly to press said roller against said inking pad, and means for swinging said bail downwardly in opposition to said spring means comprising a plunger rod slidably extended into said casing and slidably inwardly thereof by finger pressure, a rocker pivoted in said casing above said bail for swinging about an axis parallel to the axis of swinging movement of the bail and to which said plunger is pivoted to swing the same upwardly when said plunger is slid inwardly, and means for swinging said bail downwardly by upward swinging of said rocker comprising a pulley mounted to said casing, and a flexible pull member extending downwardly from said rocker around said pulley to said bail in the upswung position of said bail and connected at its opposite ends to said rocker and bail.
